UNITED STATES PATENT OFFICE.

GEORGE B. JACKSON, OF WESTMINSTER, MARYLAND.

TORPEDO.

1,182,767.

specification of Letters Patent.

Patented May 9, 1916.

Application filed January 27, 1910. Serial No. 540,354.

To all whom it may concern:

Be it known that I, GEORGE B. JACKSON, a citizen of the United States, and a resident of Westminster, Carroll county, Maryland, have invented certain Improvements in Torpedoes, of which the following is a specification.

My invention relates to track torpedoes employed for signal purposes; and the object of my invention is to provide a torpedo of such a character that the envelop or container for the detonating material may perform the function of securing the torpedo to the head of a rail. Such envelop or container may be of metal, and when such material is used, a further object of my invention is to provide the metal envelop with a cover designed to add strength thereto and to prevent the detonating material leaking out should the metal container become punctured or broken. These and other features of my invention are fully shown in the accompanying drawings, in which:

Figure 1, is a view illustrating my improved torpedo in place upon the head of a rail; Fig. 2, is a perspective view illustrating the tubular body forming the envelop for my improved torpedo; Fig. 3, is a sectional view on the line *a—a*, Fig. 2, showing the detonating material in position; Fig. 4, is a similar sectional view of a finished torpedo; Figs. 5 and 6, are views illustrating modifications embodying my invention; Fig. 7, is a perspective view of a torpedo as prepared for sale before being applied to the head of a rail, illustrating also a supplemental covering for the container or envelop; Fig. 8, is a cross-sectional view of the central portion of the structure shown in Fig. 7, and Fig. 9, is a similar view of another form of structure within the scope of my invention.

The envelop or container, which, with the detonating material forms my improved torpedo is preferably of a ductile metal, one that is soft, melting at a relatively low temperature, disintegrating readily when the torpedo explodes, and therefore incapable of causing much damage. Lead is the material preferred, and for the purpose of preparing my improved torpedo, such lead container may be made in tubular form, subsequently cut into sections of the desired length. It may be made, however, from sheet lead bent into tubular form.

An envelop or container of tubular form is illustrated in Fig. 2, and indicated at 1. The detonating material, indicated at 2, may be introduced, as shown in Fig. 3, and then the portions of the tube between the ends 60 of the same and the body of detonating material may be flattened as illustrated at 3, in Fig. 4, confining the detonating material in substantially the central portion of the tubular envelop or container. The ends 65 of the container may be turned over as indicated at 4 to avoid danger of losing the contents. The flattened portions 3 of the structure serve as the means for retaining the torpedo to the head of a rail, as clearly 70 indicated in Fig. 1; such portions possessing sufficient stiffness to form a clamp for this purpose.

In some instances, I may crimp the envelop or container adjacent the body of detonating material, as illustrated at 5 in Fig. 5. In other instances, the detonating material may be carried by an independent envelop or container 6, of paper, fabric, or any other suitable material, which may be 80 introduced into the tubular metallic structure and disposed substantially in the center of the same, as indicated in Fig. 6; the metallic container being subsequently flattened beyond the body of detonating material and having its ends turned over in the same manner as indicated with respect to the structure shown in Fig. 4. The container 6 may be of waterproof material, if 85 desired.

In Fig. 7, I have shown a torpedo made in accordance with my invention and provided with a cover or covering 7 of paper, fabric or other suitable material to add strength to the metal container or envelop 95 and prevent the detonating material leaking should the metal portion become punctured or broken. This cover may be waterproof, if desired. Fig. 8 is a sectional view of the central portion of the torpedo illustrated in Fig. 7, showing the covering for the metal envelop.

The essential feature of my invention is the use of the container or envelop as the means for securing the torpedo to the head 105 of a rail.

I claim:

1. A torpedo comprising a seamless tubular container for explosives, the ends of the container being of sufficient length to em- 110

brace the head of a rail, said ends forming 5
clamping means whereby the torpedo
may be secured to said head.

2. A torpedo comprising a seamless tubular metal container for an explosive, the 10
ends of said container being of sufficient length to embrace the head of a rail, said ends forming clamping means whereby the torpedo may be secured to said head.

10 3. A torpedo comprising an elongated tubular metal container, and detonating material disposed within the same and centrally located with respect thereto, the ends 15
of said container being flattened and of sufficient length to embrace the head of a rail, said ends forming clamps to secure the torpedo to said head.

4. A torpedo comprising a tubular container for explosives, the ends of the container being of sufficient length to embrace the head of a rail, said ends forming 20
clamping means whereby the torpedo may be secured to said rail head.

5. The combination, in a torpedo, of a 25
metallic tube, a body of detonating material within the same, and an independent envelop for said detonating material designed to position the same with respect to the tube, said tube being of sufficient length to 30
embrace the head of a rail and the ends of the same forming clamping means whereby the torpedo may be secured to said head.

6. The combination, in a torpedo, of a metallic tube, a body of detonating material

within the same, and an independent envelop for said detonating material designed 35
to position the same with respect to the tube, said tube being of sufficient length to embrace the head of a rail and the ends of the same being flattened and forming 40
clamping means whereby the torpedo may be secured to said head.

7. The combination, in a torpedo, of a tubular metallic container, a body of detonating material within the same, an independent envelop for said detonating material 45
designed to position the same with respect to the container, and a reinforcing cover of paper for the tubular metallic container, said container being of sufficient 50
length to embrace the head of a rail and having flattened portions with closed terminals beyond the detonating material, said flattened portions forming clamping means whereby the torpedo may be secured to said 55
head.

8. An improved railway torpedo comprising a one-piece tubular metallic explosive-containing case having integral extended ends forming means whereby the torpedo 60
may be clamped to the head of a rail.

In testimony whereof, I have signed my name to this specification, in the presence of two subscribing witnesses.
